UNITED STATES PATENT OFFICE

2,058,304

AMUSEMENT DEVICE

Frank H. Forrest, Springfield, Mo.

Application May 3, 1934, Serial No. 723,779

1 Claim. (Cl. 273—98)

The invention relates to amusement devices for children and has for its object the provision of a device simulating ball-throwing target devices commonly used in amusement parks, fair grounds, etc., in which the ball is secured to a resilient string to be aimed at an opening in a screen, a figure target being pivotally mounted behind the screen and visible through the opening and adapted to be knocked down when being struck by the ball when properly aimed.

The invention will be described in detail hereinafter and will be found illustrated in the accompanying drawing, in which

Figure 1 is a side view in elevation of the improved toy,

Figure 2, a top plan view,

Figure 3, a front view in elevation,

Figure 4, a transverse sectional view on a plane indicated by the line 4—4 of Figure 2, and

Figure 5, a fragmentary longitudinal sectional view on a plane indicated by the line 5—5 of Figure 2.

In the drawing similar reference characters are used to designate corresponding parts in all of the views.

The toy is self-contained and portable, including a base 10 on which is secured an inverted U-shaped frame 11 by means of driven fastenings 12 secured to outstanding feet 13 on the lower ends of said frame 11. Secured to the frame 11 is a screen 14 of any suitable fabric, and having an opening 15 therein. 16 designates a figure secured to a shaft 17, that is journaled in a U-shaped bracket 18 secured to the base 10 adjacent to the rear side of the screen 14, and when in its upright position the head portion of the figure 16 is visible through the opening 15. Also secured to the base 10 are spaced posts 19, said posts being at a distance from the front side of the screen 14, and have secured thereto a resilient string 20, preferably of rubber and have mounted thereon a ball 21. The ends of the string 20 may be secured in any suitable manner to the posts 19,

a preferred means being disclosed in the drawing and consisting of transverse slots 22 opening through the upper end of said posts 19 to receive the string 20, the ends of the string being provided with knots 23.

By having the string 20 and ball 21 on a plane considerably below the plane of the opening 15 it will be apparent that considerable skill must be displayed in aiming the ball so that it will fairly strike the head of figure 16 exposed through the opening.

The rear end of the base 10 has a reduced extension 24 for convenience in handling the toy, and has secured thereto a triangular block 25 to sustain the impact of the figure 16 when knocked down during playing of the game.

In playing with the toy the figure 16 is arranged in upright position so that the head is visible through the opening 15, and the object is to knock down the toy by striking it with the ball 21, the string 20 being stretched into the position shown in dotted lines in Figures 1 and 2, the device creating amusement for children as well as adults, simulating ball-throwing target devices, hereinbefore referred to, as being common on fair grounds, amusement parks and the like.

I claim as my invention:

An amusement device, comprising a base member, a screen member mounted on said base, and having a target opening therein, a U-shaped bracket mounted on said base member and spaced from said screen at one side thereof, a figure pivotally secured to said bracket and having a head presented in said opening in one of its positions, said figure inclining against the screen in upright position, spaced posts secured to said base member on the opposite side of said screen from the bracket and figure and having transverse slots in their upper ends, a resilient string secured in said slots, and a projectile mounted on said string intermediate of the posts.

FRANK H. FORREST.
